(57) **CLAIM**

The ornamental design for a chopping board, as shown and described.

DESCRIPTION

FIG. 1 is a top view of a chopping board of the present design with handle thereon;

FIG. 2 is a top view of the chopping board of FIG. 1 without the handle thereon;

FIG. 3 is a side view of the chopping board of FIG. 1;

FIG. 4 is a side view of the handle of FIG. 1;

FIG. 5 is a bottom view of the handle of FIG. 1;

FIG. 6 is a top perspective view of the chopping board of FIG. 1 with handle thereon; and,

FIG. 7 is a bottom perspective view of the chopping board of FIG. 1.

The shading in the figures show contour, not surface ornamentation, and form no part of the claimed design.
